CONDIMENT DISPENSER

John W. Kuhn, 1101 NE. 23rd St., Pompano Beach, Fla.
Filed Dec. 29, 1964, Ser. No. 421,802
11 Claims. (Cl. 222—131)

This invention relates to a dispensing receptacle and more particularly to an improved condiment dispenser for granulated substances such as sugar, salt, pepper, and the like.

Salt and other condiments are highly absorbent and consequently will absorb moisture when exposed to damp air and will adhere to a damp surface. As a result, the moistened condiments clog the outlet of the dispenser. Such a condition exists especially in semi-tropical climates where the relative humidity often approaches the saturation point.

Therefore, it is the primary object of this invention to provide an apparatus which overcomes the defects of prior condiment dispensers and retains condiments in a normally dry and free-flowing condition. Accordingly, the dispenser is particularly adaptable for use in kitchens despite being exposed to steam, on a boat despite the high humidity due to moisture in the air, and in semi-tropical climates where the humidity approaches the saturation point.

It is a further object of this invention to provide a dispensing apparatus which utilizes no moisture-absorbent material within or without the container to keep the condiments dry and free flowing. Accordingly, there is no problem of accidentally dropping the condiment dispenser in water or having the absorbent material saturated with moisture due to high humidity.

It is a further object of this invention to provide a dispensing apparatus which has no moving parts. Accordingly, the dispenser is simple and easy to manufacture. The simplicity of the dispenser results in a lower manufacturing cost which can be quite important in the manufacture of relatively inexpensive items with a low margin of profit.

It is a further object of my invention to provide a condiment dispenser which has few parts and can be assembled easily. Furthermore, it will be appreciated the disassembly of the dispenser is likewise accomplished easily so that the dispenser can be readily cleaned in water. Without tiny holes in which water and/or condiment particles can be trapped, the dispenser can be easily cleaned and dried.

More specifically, it is an object of this invention to provide a dispensing container comprising a hollow body provided with a threaded neck having an opening bounded by an annular end wall; a delivery member having at its upper end portion a centrally apertured, annular flange seated on the end wall and a substantially downwardly extending, open-ended, first delivery tube integral with the flange; a screw cap comprising a skirt threaded on the neck, a centrally apertured top overlying the flange and holding it on the end wall, and a second delivery tube integral with and extending from the top and registering at its lower end with and seated upon the upper end of the first delivery tube, the flange of the delivery member and the top cap partially defining a dead air insulating space; and a closure for the aperture in the cap comprising a body having a depending plug adapted to enter the aperture in the cap and an outwardly projecting flange having a downwardly projecting skirt seated upon the top of the cap.

It will be appreciated that the closure not only prevents moisture from entering the dispensing container body, but it also prevents dust and other unsanitary particles from being mixed with the condiment. Furthermore, it is an object of this invention to provide the cap with an

2

uppermost or outer surface which is substantially flat so that the dispensing container can be inverted and supported on this substantially outer surface of the top. Furthermore, it is also an object of this invention to provide a second dead air insulating space within the closure itself, defined by the flange and downwardly projecting skirt of the closure and the top of the screw cap.

It is also an object of this invention to make the lower end of the second delivery tube extend naturally below the upper end of the first delivery tube so that when the lower end of the second delivery tube is seated on the upper end of the first delivery tube, the delivery member, the screw cap, and hollow body will be biased into tight engagement.

It is still a further object of this invention to provide a means by which a measured predetermined amount of condiment can be discharged from the container so as to prevent excessive or insufficient seasoning. This feature is particularly beneficial in relatively dark eating places, such as lighted by candle, where it is difficult to tell how much seasoning is being dispensed on the food. In order to achieve an appropriate pre-measured amount of seasoning, the first delivery tube extends inwardly to a point near or in the vicinity of the bottom of the hollow body of the dispensing container. The amount of condiment which is dispensed in each operation is determined in part by the size of the opened lower end of the first delivery tube and in part by the distance at which the lower end of the delivery tube is disposed from the bottom wall of the hollow body. Accordingly, when the dispensing container is inverted, that portion of the condiment positioned above the opening and between the opening and the bottom wall of the hollow body will be dispensed through the first and second delivery tubes.

It is still a further object of this invention to provide a reliable dispensing container, the upper parts of which can be easily adapted to any type of hollow body.

These and other objects of this invention are more clearly depicted in the following detailed description having specific reference to the attached drawings in which the embodiments of the invention are shown, not to limit the scope of the invention in any respect but so that the principles thereof might be more clearly demonstrated.

In the drawings:

FIGURE 1 is a longitudinal vertical sectional view taken through the condiment dispenser constructed in accordance with the present invention;

FIGURE 2 is a longitudinal vertical sectional view taken through a condiment dispenser having a modified screw cap and closure;

FIGURE 3 is a fragmentary longitudinal vertical sectional view taken through a condiment dispenser showing further modification in the closure, screw cap, and delivery members;

FIGURE 4 is a view similar to FIGURE 2 but having the closure removed and showing the dispenser in an inverted position;

FIGURE 5 is a fragmentary longitudinal vertical sectional view of a condiment dispenser shown without the closure and having a still further modified screw cap and delivery member; and

FIGURE 6 is a sectional view taken substantially along the lines 6—6 of FIGURE 1 and showing a transverse sectional plan view of the dispenser in its entirety with the condiment removed.

Referring now to the drawings in detail, a condiment dispenser 10 is shown broadly comprising a hollow body 12 and a dispensing cap portion 14. The hollow body 12 of the condiment dispenser constitutes a receptacle for condiments 16 such as sugar, salt, pepper and the like. The hollow body is shown in this instance made

of glass, although it may be made from any other suitable material such as plastic or the like. Furthermore, the container may be of any conventional design although it is preferably of the shape disclosed in FIGURE 1. The hollow body 12 has a threaded neck 18 which is preferably threaded externally so as to detachably receive the dispensing cap portion 14. The threaded neck 18 has an opening 20 extending therethrough and communicating with the hollow body 12. The opening 20 is bounded and defined by an annular end wall 22.

The dispensing cap portion 14 is preferably made of some non-corrosive material, such as plastic, and broadly comprises a delivery member 24, a screw cap 26 and a closure 28. The delivery member extends within the hollow body 12 and comprises a first delivery tube 30 having an annular flange 32 integrally attached to its upper end portion 34. By its very definition the first delivery tube has a tubular opening 36 extending axially therethrough thereby providing a central aperture in the annular flange 32. The first delivery tube extends downwardly into the hollow body to a position disposed a certain distance 38, shown in FIGURE 4, from the inner surface 40 of the base wall 42 of the hollow body 12. The lower end 44 of the first delivery tube is preferably outwardly flared so as to provide a mouth for catching that portion of the condiment disposed between the lower end 44 of the first delivery tube 30 and the inner surface 40 of the base wall 42 when the condiment dispenser is inverted.

The annular flange 32 is seated on the annular end wall 22 defining the opening 20 in the threaded neck 18 and thereby holds the depending first delivery tube 30 in a suspended position with the hollow body 12. As illustrated in FIGURE 1, the annular flange is attached at the extreme upper end 46 of the first delivery tube and is inclined upwardly and outwardly to its seated position on the annular end wall 22. It will be appreciated, however, that the annular flange could extend merely outwardly, as illustrated in FIGURE 5, and that it could be attached at a position slightly below the extreme upper end 46 of the first delivery tube, as illustrated in FIGURE 3.

The screw cap 26 is designed to hold the delivery member in place by holding the annular flange 32 in a substantially immovable seated position on the annular end wall 22. Accordingly, the screw cap comprises a skirt 48 threaded on the neck 18 of the hollow body 12 integrally connected to a top 50 having a central aperture 52 therein. The top is positioned so that it overlies the flange 32 and is so configured that its outer portion 54 engages the flange at the point where the flange is seated on the annular end wall 22. The top 50 has an integral second delivery tube 56 extending therefrom, preferably as disclosed in FIGURE 1, in a downward direction. The second delivery tube by its very definition has an opening 58 extending therethrough and contiguously aligned with the central aperture 52 of the top 50. The lower end 60 of the second delivery tube 56 registers with and is seated upon the extreme upper end 46 of the first delivery tube. As illustrated, the opening 58 preferably has a frusto-conical shape of diminishing cross-sectional area as the opening extends upwardly to a flared seat 62 on the upper end 64 of the second delivery tube 56. The base of the frusto-conical opening 58 is preferably contiguously aligned with the upper end of the opening 36 extending through the first delivery tube 56.

It is within the scope of the invention to make the second delivery tube 56 of such a length that its lower end 60 extends naturally below the upper end 46 of the first delivery tube 30 when the top 50 is in position to hold the flange 32 seated on the annular end wall 22. Since the lower end 60 of the second delivery tube registers with the upper end 46 of the first delivery tube, it is necessary to make the flange 32 slightly flexible to ac-

commodate the extra length of the second delivery tube. Consequently, manufacturing tolerances do not have to be too limited, and more important the resilient tendency of the flange 32 to return to its normal position causes the first and second delivery tubes, and accordingly, the delivery member, screw cap, and hollow body, to be biased into tight engagement.

The inner portion 66 of the top 50 overlies the annular flange 32 and is disposed therefrom so as to partially define with the flange a first dead air insulating space 68. This insulating space is also defined by the second delivery tube in FIGURES 1, 2, 4, and 5. In FIGURE 3 it will be seen that the first delivery tube rather than the second delivery tube also defines this space. Although the first delivery tube is substantially downwardly extending from the flange 32, it is within the scope of the invention to extend the first delivery tube above the flange, with this upper portion defining the dead air insulating space. Accordingly, the flange is attached at the upper end portion 34 of the first delivery tube, but at a position disposed from the extreme upper end 46. This dead air insulating space retards condensation of moisture on the inner walls of the first delivery tube defining the opening 58 and on that portion of the annular flange 32 facing inwardly of the hollow body 12.

The closure 28 for the aperture 52 in the top 50 of the screw cap 26 comprises a body 72 having a depending plug 74 adapted to enter the aperture 52 and an outwardly projecting flange 76 with a downwardly projecting skirt 78. The downwardly projecting skirt is preferably circular and engages a corresponding preferably circular shoulder 80 formed integrally with the upper surface 82 of the top 50 of the screw cap. As illustrated in the various figures, the shoulder 80 can take numerous configurations and can face outwardly or inwardly. Essentially, however, the shoulder provides a means by which the closure is centered on the screw cap. It is within the scope of the invention to eliminate the shoulder and have the screw cap centered merely by the plug 74 itself. In the preferred embodiment of the invention, the depending plug 74 is formed integrally with the body 72. It will be appreciated, however, that the plug could comprise a separate element which is detachably secured in the closure 28.

It is preferable to have the outwardly projecting flange 76 at least partially disposed from the top 50 of the screw cap 26 so that the flange 76 and downwardly projecting skirt 78 of the closure 28 and the top 50 of the screw cap 26 define a second dead air insulating space 84 which prevents moisture from accumulating around the flared seat 62 of the upper end 64 of the second delivery tube 56.

Furthermore, it is within the scope of this invention to eliminate the closure so that the dispensing container could be supported by the screw cap in an inverted position as shown in FIGURE 4. Accordingly, the apertured top 50 of the screw cap could comprise a substantially flat outer surface 86 and an inner surface 88 operatively connected to the outer surface and defining a recess 90 therein. The shoulder 80 could be eliminated if the closure was eliminated. However, in order to make the screw cap usable with or without the closure, it is contemplated that the shoulder could in fact comprise part of the inner surface 88 as illustrated in FIGURE 2. It will be seen that when the condiment dispenser is inverted, the recess 90 provides an insulating air pocket for retarding the accumulation of moisture around the flared seat 62 on the upper end 64 of the second delivery tube.

From the foregoing description, it is apparent that the dispensing cap portion comprising the delivery member, screw cap, and closure could be attached to any type of dispensing container which has a threaded neck and which will accommodate the depending first delivery tube interiorly thereof so that the lower end of the first

delivery tube extends to a point within the vicinity of the base wall of the hollow body.

While a preferred form of the invention has been illustrated in the drawings and discussed above, it should be adequately clear that considerable modification may be made thereto without departing from the principles of the invention. Therefore, the foregoing should be considered in an illustrative sense rather than a limiting sense, and accordingly the extent of this invention should be limited only by the spirit and scope of the claims appended hereto.

I claim:

1. A dispensing container for condiments comprising a hollow body provided with a threaded neck having an opening bounded by an annular end wall; a delivery member having at its upper end portion a centrally apertured, annular flange seated on the end wall and a substantially downwardly extending, open-ended, first delivery tube integral with the flange; a screw cap comprising a skirt threaded on the neck, a centrally apertured top overlying the flange and holding it on the end wall, and a second delivery tube integral with and extending from the top and registering at its lower end with and seated upon the upper end of the first delivery tube, the flange of the delivery member and the top of the cap partially defining a dead air insulating space; and a closure for the aperture in the cap comprising a body having a depending plug adapted to enter the aperture in the cap and an outwardly projecting flange having a downwardly projecting skirt seated upon the top of the cap.

2. The dispensing container defined in claim 1 wherein the second delivery tube has an upright frustoconical opening extending axially therethrough.

3. The dispensing container defined in claim 2 wherein in the upper end of the second delivery tube has an outwardly flared seat.

4. The dispensing container defined in claim 2 wherein in the first delivery tube has a tubular opening extending axially therethrough, the upper end of the opening registering and being contiguously aligned with the base of the frusto-conical opening of the second delivery tube.

5. The dispensing container defined in claim 1 wherein in the depending plug is integrally connected to the body of the closure.

6. The dispensing container defined in claim 1 wherein the upper surface of the apertured top of the screw cap overlying the flange comprises a substantially flat outer surface and an inner surface operatively connected to the outer surface and defining a recess therein so that the dispensing container can be inverted and supported on the substantially flat outer surface of the upper surface of the top.

7. The dispensing container defined in claim 1 wherein the flange of the delivery member is upwardly and outwardly inclined.

8. The dispensing container defined in claim 1 wherein the outwardly projecting flange of the closure is at least partially disposed from the top of the screw cap and wherein the flange and the downwardly projecting skirt of the closure and the top of the screw cap define a second dead air insulating space.

10 9. The dispensing container defined in claim 1 wherein the lower end of the depending second delivery tube extends naturally below the upper end of the first delivery tube so that when the lower end of the second delivery tube is seated on the upper end of the first delivery tube, the delivery member, the screw cap, and hollow body will be biased into tight engagement.

15 10. The dispensing container defined in claim 1 wherein in the flange of the delivery member is upwardly and outwardly inclined, the second delivery tube extends upwardly from the cap with its lower end registering with and seated upon the upper end of the first delivery tube, and the annular flange is attached at the upper portion of the first delivery tube at a position disposed from its upper extreme end, and wherein the upper portion 20 25 of the first delivery tube, the flange, and the top of the cap define a dead air insulating space.

11. A dispensing container for condiments comprising a hollow body provided with a threaded neck having an opening bounded by an annular end wall; a delivery member having at its upper end an upwardly and outwardly inclined, centrally apertured, annular flange seated on the end wall and a downwardly extending, open-ended, first delivery tube integral with the flange; a screw cap comprising a skirt threaded on the neck, a centrally apertured top overlying the flange and holding it on the end wall and having a circular shoulder on its upper surface, and a depending second delivery tube integral with the top and registering at its lower end with and seated upon the upper end of the first delivery tube, the flange of the delivery member and the top and the second delivery tube of the cap providing a dead air insulating space; and a closure for the aperture in the cap comprising a body having an integral, depending plug adapted to enter the aperture in the cap and an outwardly projecting flange having a downwardly projecting skirt seated upon the top of the cap and centered by engagement with the circular shoulder thereon.
